UNITED STATES PATENT OFFICE.

ANTOINE MARIE LOUIS MATHIOLY, OF L'ISLE-EN-JOURDAN, FRANCE.

BROILER.

SPECIFICATION forming part of Letters Patent No. 320,668, dated June 23, 1885.

Application filed September 12, 1884. (No model.) Patented in England April 22, 1884, No. 6,636, and in France December 18, 1884, No. 159,250.

To all whom it may concern:

Be it known that I, ANTOINE MARIE LOUIS MATHIOLY, a resident of L'Isle-en-Jourdain, in the French Republic, and a citizen of said 5 French Republic, have invented certain new and useful Improvements in Broilers; and I do hereby declare the following to be a full, clear, and exact description of the invention, such as will enable others skilled in the art to 10 which it appertains to make and use the same, reference being had to the accompanying drawings, and to letters or figures of reference marked thereon, which form a part of this specification.

15 This invention has for its object certain improvements in gridirons, whereby the efficiency of use, as well as the durability of such utensils, is materially enhanced; and it consists, in combination with a gridiron, with or without 20 fixed legs, of foldable and vertically-adjustable legs, whereby the proximity of the utensil to the combustible may be adjusted within certain limits.

The invention further consists in the combination, with the gridiron, of a fire-guard 25 to protect the food placed thereon against the action of the fire when the utensil is employed for cooking food in an open fire-place.

The invention further consists in certain 30 tails of construction, all substantially as hereininafter more fully described, and as illustrated in the accompanying drawings, and in which—

Figure 1 is a side elevation of the gridiron, the adjustable legs being folded up. Fig. 2 is 35 a like view with the adjustable legs turned down. Fig. 3 is a perspective view of the gridiron; and Figs. 4 and 5 are detail views.

The gridiron proper, A, may be constructed in any usual or preferred manner, and be composed of any number of wires, a, arranged transversely or longitudinally, or in any other desired manner, and at any desired distance from one another, according to the uses made of the gridiron.

40 For use in open fire-places I provide the utensil with four stationary legs, a', secured to the corners thereof, though these may be dispensed with when the gridiron is designed for use both on a stove and in an open fire-place.

45 In either of these cases it is desirable to pro-

vide means whereby the distance of the article treated relatively to the source of heat may be regulated, and to this end I employ foldable legs adapted for vertical adjustment, constructed and arranged as follows: The two 55 pairs of adjustable legs L and L' are each formed of a single wire bent at right angles, to form at each end the legs proper, and having the central cranked portion, l. The wires L L' are pivoted in loops l', secured to or formed 60 by two of the wires a of the gridiron at suitable points, and to the cranked portion l of each wire L L' is connected one end of a connecting rod or wire, W W', the former rod, W, being connected to crank l of wire L, and 65 the rod W' to the like crank of wire L'. The opposite ends of the connecting-rods W W' are connected to opposite ends of a cross-head, C, formed by a wire secured to a boss or foot-piece, B, to which is also secured the operating wire or rod R.

H is the handle of the gridiron, formed by one or two wires, h, arranged to form at their outer end a suspension-loop, h'. These wires are secured within a sheet-metal inclosing- 75 sleeve, S, that has openings 5 above and below the handle-wires, through which the operating-rod R passes, said rod projecting some distance above the sleeve S, at which point it is bent to form a loop or hand-hole, r; the extension r' of said bent portion having its outer or free end, r', bent at right angles to form a hook, r'', adapted to engage one of the holes 1, 2, 3, or 4, formed in the sleeve S.

When the parts are in the position shown in 85 Fig. 3, the hook r'' of the locking-arm r' of the handle being in engagement with the hole 1, the legs L L' will be fully extended and the gridiron will rest thereon solely, the legs a being elevated from the supporting surface 90 of the gridiron. If it is desired to bring the gridiron closer to the source of heat, it will only be necessary to raise the same slightly by seizing it with the left hand by the handle and when slightly raised turning the operating-rod R in the direction of the arrow x, Fig. 3, until the hook r'' of locking-arm r' engages the hole 2. This partial rotation of the rod R imparts a like rotation to the cross-head C, and through the connecting-rods W W' the 95

two pairs of legs L L' will be moved in opposite directions, or from each other. By bringing the hook of the locking-arm r' into engagement with the hole 3 the two pairs of legs L L' will be moved still farther from each other and the gridiron correspondingly lowered, and by moving the arm r' so that its hook will engage the hole 4 the two pairs of legs L L' will be fully folded up, as shown in Fig. 1. When the parts are in the position last above described, and shown in said Fig. 1, the gridiron will rest on the fixed legs a' and on the foot-piece or boss B, as shown. By means of this construction I provide a support for the gridiron at five points—namely, at the four corners and at the handle—thus avoiding any liability of upsetting.

When broiling or toasting in an open fireplace, the food upon the gridiron is liable to be scorched and burned or become smoked by the wood or coal fire back of it. To avoid this I apply to the rear end of the gridiron a guard-plate, G, extending vertically therefrom, whereby such food is effectually protected from the action of the fire back of the gridiron. This guard-plate may be soldered to the front cross-wire, a^2 , of the gridiron, or it may be detachably connected therewith by forming at each corner a loop or eye, a^3 , and securing to the ends of the sheet-metal guard G leg-wires g , adapted to be stuck into said loops, as shown in Fig. 5. In this manner the guard G may be readily removed when its use is not required, and when worn out from any cause it may be readily removed and a new one substituted at a trifling expense.

Instead of the sheet-metal sleeve S, the handle may be formed entirely of wires bent into the shape of loops or eyes 1, 2, 3, 4, and 5, the loop or eye 5 serving as a bearing for the rod R, as shown in Fig. 4. I prefer, however, to employ the metallic sleeve S, for the reason that it furnishes a re-enforce to the handle and a more substantial bearing for the said rod R underneath and above the handle-wires.

If desired, brace-wires D D may be secured to the under side of the sleeve S, and their outer ends bent into the form of a loop or eye, $d d$, through which the rod R may be passed to provide a still more secure bearing for said rod, as shown.

Having now particularly described my said invention, what I claim as new, and desire to secure by Letters Patent, is—

1. The combination, with a gridiron, of adjustable legs whereby said gridiron may be adjusted vertically relatively to the source of heat, for the purpose specified. 55
2. The combination, with a gridiron, of a detachable guard-plate, G, applied to one end 60 of the gridiron, substantially as and for the purpose specified.
3. The combination, with a gridiron provided with fixed supporting-legs, of adjustable auxiliary legs of greater length than the 65 fixed legs, for the purpose set forth.
4. The combination, substantially as herein described, with a gridiron, of adjustable legs, an operating-rod connected with said legs, and a stop for locking the legs in position when 70 adjusted, for the purpose specified.
5. The combination, substantially as herein described, with a gridiron, of adjustable legs, a cross-head, connecting-rods for connecting said legs with the cross-head, and a stop for 75 locking the cross-head into position, for the purpose set forth.
6. The combination, substantially as herein described, with a gridiron and its handle, of four adjustable legs arranged in pairs, a cross- 80 head, connecting-rods for connecting the legs in pairs to opposite ends of the cross-head, an operating-rod for rotating said cross-head, and stops formed on or secured to the handle for locking the cross-head in position when ad- 85 justed, for the purposes specified.

7. The combination, substantially as herein described, with the gridiron A, its handle H, and the sleeve S, provided with holes 1 2 3 4 5, of the legs L L', the rods W W', the cross- 90 head C, the rod R, and locking-arm r' , for the purpose specified.

In testimony that I claim the foregoing I have hereunto set my hand this 20th day of August, 1884.

ANTOINE MARIE LOUIS MATHIOLY.
